Primary Examiner — Bao-Yen T Nguyen*Assistant Examiner* — Christopher John Suarez La Rosa(74) *Attorney, Agent, or Firm* — McNees Wallace & Nurick LLC(57) **CLAIM**

The ornamental design for a pack, as shown and described.

DESCRIPTION

FIG. 1 is a top-front-left perspective view of a pack, showing the design;

FIG. 2 is a bottom-rear-right perspective view thereof;

FIG. 3 is a front view thereof;

FIG. 4 is a right view thereof;

FIG. 5 is a rear view thereof;

FIG. 6 is a left view thereof;

FIG. 7 is a bottom view thereof;

FIG. 8 is a top view thereof; and,

FIG. 9 is a side perspective view thereof.

The broken lines in the drawings illustrate portions of the pack that form no part of the claimed design.

1 Claim, 9 Drawing Sheets
